CLAIM

The ornamental design for a curved handle pendulum putter, as shown and described.

DESCRIPTION

FIG. 1 is a perspective view of the curved handle pendulum putter.

FIG. 2 is a rear plan view of the invention.

FIG. 3 is a front plan view of the invention.

FIG. 4 is a left side elevational view of the invention.

FIG. 5 is a right side elevational view of the invention.

FIG. 6 is a top plan view of the invention; and,

FIG. 7 is a bottom plan view of the invention.

The broken line showing of the putter head is for illustrative purposes only and forms no part of the claimed design.
